UNITED STATES PATENT OFFICE.

DAVID J. RICHARDSON, OF PITTSBURGH, PENNSYLVANIA.

LOCK FOR BOXES.

1,239,725.

Specification of Letters Patent. Patented Sept. 11, 1917.

Application filed November 8, 1916. Serial No. 129,251.

To all whom it may concern:

Be it known that I, DAVID J. RICHARDSON, a citizen of the United States, and residing in the city of Pittsburgh, in the county of 5 Allegheny and State of Pennsylvania, have invented or discovered new and useful Improvements in Locks for Boxes, of which the following is a specification.

My invention consists in a new and improved 10 container for the mailing or shipment of valuables, such as currency, bonds, stock certificates, &c.

The object in view is the provision of a 15 container of light and inexpensive construction which will automatically lock itself shut when closed, and which, after the container is once closed, cannot be opened or access had to the locking means without mutilating the 20 container in such a manner that the fact that it has been tampered with is advertised and its re-use is rendered impossible.

For the accomplishment of this purpose, I 25 form my container of telescoping boxes, preferably of card or light fiber board and provide a novel form of automatic locking 30 means so protected by the material of the boxes that it cannot be tampered with or rendered inoperative without materially mutilating and destroying the container.

35 Novel features of construction and arrangement of parts will appear from the following description.

In the accompanying drawings, Figure 1 is a perspective of my container closed and 40 locked, ready for the mail; Fig. 2 is a broken vertical longitudinal section of the same; Fig. 3 is a broken plan view showing the inner box nested in the intermediate box; Fig. 4 is a broken perspective showing the interior 45 of the intermediate box; Fig. 5 is a broken perspective, showing the interior of the outer box reversed, and Fig. 6 is a vertical section showing the outer box and the intermediate box locked together, the inner box being omitted.

The following is a detailed description of the drawings.

The container is comprised of an outer 50 box A, a second or intermediate box B, and, preferably, an inner or third box C, all having their tops open. The box B nests snugly in the box A, its open top being inserted into the box A while the box C is of the proper width to nest snugly in the box B, with its 55 open top inserted in the box B, but the box

C is short enough to provide room for the locking means at one or both of the ends of the intermediate box.

These boxes may be made of any suitable material; but I prefer to use stiff yet flexible card or fiber board for that purpose.

Permanently fixed against the inner face of one or both of the end walls of the box B is a block 1 of wood or other light yet strong material, preferably substantially 65 covering such end wall and secured immovably thereto, as by rivets 2. The upper end of said block is beveled, as shown at 3 and provided below the bevel with a transverse angular and preferably undercut locking 70 slot 4.

5 is a locking plate of spring metal, firmly secured, as by rivets 6 to the inner wall of the outer box A and having a downwardly extending hooked grip 7 which when the 75 boxes A and B are telescoped together is first sprung inwardly by the beveled portion 2 of the block 1 and then springs outwardly into positive engagement with the slot 4.

The presence of the inner box C within 80 the box B prevents the movement of the grip 7 inwardly out of engagement with the slot 4 when the box is once locked closed, while it does not interfere with the locking operation as the grip 7 is in such case sprung together as it is inserted down between the beveled portion of the block 1 and the adjacent end of the inner box C.

In use, the currency or other valuable is first packed in the inner box C and the latter 90 nested in the box B. The outer box A is now telescoped down over the box B, the spring grip 7 being compressed and inserted between the block 1 and the end wall of box C. When the box B is properly nested in 95 the box A, the grip springs or expands into locking engagement with the slot 4, thus locking the container closed.

When the container has arrived at its destination and is to be opened, a knife is used 100 to cut the top of box A so as to detach the locking plate 5 from said box; whereupon the box A may be removed and the boxes B and C unnested. It is evident that this entails the permanent mutilation and destruction of the outer box, so that the container cannot be opened or its contents tampered with in transit, without that fact being advertised. The locking plate 5 and the block 1 are inaccessible unless the container 110

is mutilated and the body of the block 1 prevents access to the grip 7 from above or below.

If desired, the inner box C may be omitted and the contents packed in the box B, but I prefer to use the inner box C for receiving the contents as its end wall aids in holding the hooked grip and locking block in engagement.

10 When a package of currency or jewelry is to be sent by mail or express, the container is filled and locked shut by an authorized person, and, when received by the consignee, the condition of the container will indicate whether or not its contents are intact. If the container is cut open, then it has been tampered with; otherwise the contents are as shipped. Thus claims of shortage or improper filling of an order may be 15 easily investigated and the responsibility fixed on the proper person.

What I desire to claim is:—

1. In a container for the purpose described, the combination of an outer box, a 5 second box open at its top nesting snugly in said outer box, and automatic locking means for securing said boxes together comprising

a block secured against the inner face of the end wall of the second box provided with a transverse locking recess on its exposed face and a hooked locking plate of spring metal attached to the bottom of the outer box and adapted to snap down over the exposed face of said block into engagement with said recess when said boxes are telescoped together. 30 35

2. In a container for the purpose described, the combination of an outer box, a second box open at its top nesting snugly in said outer box, automatic locking means 40 for securing said boxes together comprising a block secured against the inner face of the end wall of the second box provided with a transverse locking recess and a hooked locking plate of spring metal attached to the bottom of the outer box and adapted to snap into engagement with said recess when said boxes are telescoped together, and a third 45 box nesting in said second box and having its end wall bearing on said locking plate to prevent its disengagement from said recess.

Signed at Pittsburgh, Penna., this 19th day of September, 1916.

DAVID J. RICHARDSON.
